CARBONATED BEVERAGE DISPENSER

Angelo D. Maggiola, Sacramento, Calif.

Application May 23, 1936, Serial No. 81,491

1 Claim. (Cl. 225—22)

This invention relates to carbonated beverage dispensers and has for the primary object the provision of a device of this character which may be easily and quickly adapted to a bottle or like container in which the carbonated beverage is sold and which will open the bottle by the application thereto and provides an efficient seal to prevent deterioration of the beverage and is so constructed that the beverage may be dispensed as desired.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a fragmentary vertical sectional view illustrating a dispenser adapted to a bottle and constructed in accordance with my invention.

Figure 2 is a top plan view illustrating the dispenser.

Figure 3 is a sectional view taken on the line 3—3 of Figure 1.

Figure 4 is a fragmentary side elevation illustrating the means of securing the dispenser to the bottle.

Figure 5 is a view similar to Figure 4 showing the connection between an adjusting sleeve and an anchoring clamp.

Figure 6 is a plan view illustrating a specially constructed cap to be used on the bottle.

Figure 7 is a sectional view illustrating the cap.

Figure 8 is a side elevation illustrating a puncturing element employed for standard or caps now in use on bottles.

Referring in detail to the drawing, the numeral 1 indicates a valve housing on which is formed a nozzle 2. The valve housing 1 has a valve seat 3 engaged by a valve 4, the stem 5 of which extends through the valve housing and is equipped with a finger piece 6. A coil spring 7 surrounds the stem between the valve housing and the finger piece for urging the valve in engagement with the seat 3. The stem 5 is guided in its sliding movement by a spider 8 mounted in the valve housing. Formed on the valve housing below the valve seat is an internally and externally screw threaded sleeve 9. Threaded into the sleeve 9 is a tube 10 adapted to pass downwardly in a bottle 11 and has integral therewith a cap engaging disc 10'. The lower end of the tube 10 is internally screw threaded to receive the

screw threaded end of either of the puncturing elements 12 or 13.

When employing my invention on a bottle the latter may be equipped with a standard or ordinary type of crown cap (not shown) or the bottle may be equipped with a cap 14 secured to the neck of the bottle in the same manner as the ordinary type of crown cap. The cap 14 is offset, as shown at 15. The cap about the offset 15 is weakened so that when the puncturing element 12 is brought into engagement therewith with minimum force the material of the offset will be broken away allowing the tube 10 to pass downwardly in the bottle. A gasket 16 is arranged in the cap 14.

A bushing 17 is threaded to the sleeve 9 and is of a diameter greater than the diameter of the neck of the bottle and has threaded therein an adjusting sleeve 18. The bushing 17 is provided with a packing 19 to engage the tube 10 and sleeve 9.

A sectional clamp 20 is placed about the neck of the bottle below the usual shoulder 21 on the bottle. The sectional clamp is hinged together, as shown at 22, and is equipped with a fastener 23 whereby the clamp may be readily applied and removed from the neck of the bottle. Pivot to the clamp 20 are yokes 24 adapted to be brought in engagement with projections or keepers 25 formed on the sleeve 18. Located in the bushing 17 is a plurality of washers 26. One of the washers is preferably constructed of metal and is indicated by the character 27 while the other washers may be constructed of any suitable composition material. The washers surround the tube 10 and are interposed between the bushing 17 and the cap engaging disc 10' and with the clamp applied to the neck of the bottle and the yokes in engagement with the keepers an adjustment of the bushing 17 relative to the sleeve 18 will draw the washers in tight engagement with the bushing and the cap engaging disc 10' thereby providing an effective seal between my invention and the bottle. The valve being held in a closed position will prevent the contents of the bottle from evaporating or deteriorating.

The puncturing element 12 is provided with several prongs 28 which when brought in engagement with the offset 15 of the cap will readily penetrate the material thereof. When employing a standard type of cap commonly known as the crown cap the puncturing element 13 is employed and consists of a cone-shaped body 29, the pointed end of which will readily pass through the cap when placed in engagement with said cap with

sufficient force. The puncturing elements 12 and 13 each have a bore passing therethrough.

After the application of my invention to a bottle, as shown in Figure 1, and if said bottle contains charged beverage it is only necessary to unseat the valve 4 by pressing on the finger piece 6 so that the charged beverage may pass out of the bottle by way of the tube 10 and nozzle 2. As soon as the finger piece 6 is released the spring 7 acts to close the valve, consequently sealing the beverage against atmospheric conditions and which will prevent deterioration of the beverage. If the beverage is not charged, the valve is opened and the bottle is tilted so that the beverage may flow from the bottle by way of the tube and the nozzle.

The tubes 10 may be of different lengths so that

this device may be adapted to bottles of pint, quart and other sizes.

Having described the invention, I claim:

The combination of a bottle having a closure and a dispenser including a valve of the self-seating type, a finger piece for opening said valve, a nozzle formed on the housing for said valve, a tube detachably secured to the housing for said valve, a penetrating element detachably secured to said tube, a bushing detachably secured to the valve housing and having the tube extending therethrough, an adjusting sleeve threaded to said bushing, packing between the bushing and the closure of the bottle, a clamp detachably mounted on the neck of the bottle, yokes pivoted to said clamp, and projections formed on the adjusting sleeve to be engaged by the yokes. 5 10 15
